SHOE

Evelyn K. Lahnstein and Joseph Albert Lahnstein, New York, N. Y., assignors to Blanklette Corporation, New York, N. Y., a corporation of New York

Application February 10, 1950, Serial No. 143,392

3 Claims. (Cl. 36—2.5)

1

This invention relates to a structurally and functionally improved shoe and especially a shoe for use by small children and infants.

It is an object of the invention to furnish a foot covering or shoe which will have a pleasing appearance and which will adequately cover and protect the foot; a unit embodying the present teachings providing a structure such that adjustment may be effected as the child's foot grows so that the shoe will at no time bind the foot nor enclose it in a manner other than that which is characteristic of a properly fitting foot covering.

Accordingly, a shoe is furnished which may be purchased with assurance by the parent that it may periodically have its parts adjusted so as to provide a foot enclosure suited precisely to a child's needs as that child's foot grows.

An additional object is that of furnishing a shoe which may be economically produced and likewise sold at a relatively low figure to furnish an article which will be satisfactory to the user over long periods of time.

With these and other objects in mind reference is had to the attached sheet of drawings illustrating one practical embodiment of the invention and in which:

Fig. 1 is a perspective view of the shoe and showing the parts of the same detached from each other;

Fig. 2 is a plan view of the shoe with the parts connected; and

Fig. 3 is a side view of the device as shown in Fig. 2 with certain of the parts broken away and others of the same shown in section.

This application is a division of our earlier application for patent filed in the United States Patent Office on December 29, 1948, identified under Serial Number 67,776 and entitled "Adjustable Garment."

The reference numeral 5 indicates the outer sole which may be formed of leather or any other suitable material. This sole is provided with a liner 6 conveniently formed of cloth; the two being secured to each other and, for example, to the upper of the shoe in any desirable manner such as by stitching 7. A projecting portion generally indicated at 8 is provided adjacent the forward end of the sole and as shown may be integral with the layers of the latter. The length of this projecting portion is such that it is capable of being folded upwardly and rearwardly to overlie the upper of the shoe. To achieve this, the layers of the sole should be sufficiently flexible at points beyond the upper or else should be formed in a manner such that a hinge action may occur.

2

The upper 9 may be also formed of any suitable number of layers: If desired, these may be in the form of uninterrupted strips extending from points adjacent the forward end of the shoe rearwardly around the counter portion of the same. At the latter point they include a height such that the heel of the wearer will be snugly and properly enclosed. Their upper edges may be defined by a binding 10 which extends conveniently throughout the entire length of the assembly providing the shoe upper. These edges throughout their rear zones define an opening. Preferably the edges of this opening extend into a plane just below the ankle of the wearer. Obviously, a greater or lesser amount of material might be furnished at these points to have the shoe upper extend into a higher or lower plane. The forward ends of the strip furnishing the upper may include extensions 11. The areas of these are such that they may be overlapped to provide a foot-enclosing or vamp portion. When as shown in Figs. 2 and 3 the projecting portion 8 of the sole is extended upwardly and rearwardly it will form a toe box or shoe cap.

25 Now with a view to providing fastening means which will retain the parts in assembled condition and will also permit of those parts being adjusted with respect to each other, cooperating fastening elements are employed. Preferably these elements embrace snap fasteners of standard construction. A socket element 12 may be affixed to the projecting portion 8 of the sole adjacent its outer end and cooperate with one of a series of stud elements 13 mounted to have their projecting portions extend upwardly from that extension 11 which overlaps the innermost extension of the shoe upper. Fastening elements 13 are preferably disposed in a substantially straight line which lies at an angle to the longitudinal axis of the shoe, and with the parts assembled extends across the center of the shoe along the vamp portion.

30 The outermost extension 11 also supports socket elements 14 and 15 adjacent its forward and rear corners. These elements cooperate respectively with a series of stud elements 16 and 17 projecting upwardly from the second or innermost projecting portion 11.

35 It has been found as a consequence of this arrangement of parts that a purchaser may, with assurance, acquire a pair of shoes for a child and which shoes will properly and snugly enclose the foot of the child with socket elements 12, 14 and 15 in engagement with the rearmost elements of the series 13, 16 and 17. With the passage of

time and as the child's foot grows, the parts may be adjusted so that improper pressures will not occur. To this end, socket elements 14 or 15 may be shifted to engage the intermediate element or elements of the series 16 and 17. This will increase the width of the shoe. Likewise, when the length of the shoe is to be increased socket element 12 may be shifted to engage the second of the series of stud elements 13. Thus, the toe box or cap will be increased in length. It is apparent that in lieu of each series of fastening elements 13, 16 and 17 including three units, that a greater or lesser number might be employed. Also socket elements might be utilized in lieu of stud elements and vice versa.

Thus, among others, the several objects of the invention as specifically aforesaid are achieved. Obviously numerous changes in construction and rearrangement of the parts might be resorted to without departing from the spirit of the invention as defined by the claims.

We claim:

1. A shoe including a sole, an upper comprising integral side and rear walls attached to corresponding portions of the sole adjacent the edges of the latter, a first extension forming a part of one of said side walls adjacent the forward end thereof, a second extension forming a part of the other of said side walls adjacent the forward end thereof positionable over said first extension, a projecting portion adjacent the forward end of said sole, two series of fastening elements secured to said first extension and arranged in downwardly disposed rows, a pair of single cooperating fastening elements secured to said second extension adjacent the edge thereof, each cooperative with one of said series of fastening elements on said first extension whereby said cooperating fastening elements are selectively engageable with certain of the fastening elements on said first extension to furnish an adjustable vamp portion, a series of fastening elements on the outer surface of said second extension and disposed one to the rear of the other and a single cooperating fastening element mounted on the end of the portion projecting from the sole whereby the latter may be folded upwardly and rearwardly and secured to any of the last named series of fastening elements of the second extension.

2. A shoe including a sole, an upper comprising integral side and rear walls attached to corresponding portions of the sole adjacent the edges of the latter, a first extension forming a part of one of said side walls adjacent the forward end thereof, a second extension forming a part of the other of said side walls adjacent the forward end thereof and positionable over said first extension, a portion projecting from the forward end of said sole, a series of fastening elements secured to said first extension and arranged in downwardly disposed rows, a cooperating fastening element secured to said second extension cooperative with one of said series of fastening elements on said first extension whereby said cooperating fastening element is selectively engageable with certain of the fastening elements on said first extension to

furnish an adjustable vamp portion, a series of fastening elements on the outer surface of said second extension and disposed one to the rear of the other and a cooperating fastening element mounted on the end of the portion projecting from the sole whereby the latter may be folded upwardly and rearwardly and secured to any of the last named series of fastening elements of the second extension.

3. A shoe including in combination a sole defining an upper surface to receive and support the foot of the wearer from the heel through to the toes, a portion projecting forwardly of the toe supporting area of the sole, a strip of material having a lower edge secured to the sole, to extend around the rear of the same in line with its edge to provide a counter portion for said shoe, said strip having its lower edge secured to the sole to extend uninterruptedly forwardly of said counter portion in registry with the sole edge on both sides of the sole to a point substantially in line with the toe supporting area of said sole, a first upwardly projecting extension forming a part of said strip between the counter-providing portion thereof and one of its forward ends, a second upwardly projecting extension forming the other side of said strip between the counter-providing portion thereof and its other forward end, said second extension being positionable over said first extension across the instep of the wearer, a series of fastening elements secured to said first extension and arranged in a downwardly disposed row, a cooperating fastening element secured to said second extension cooperative with said series of fastening elements on said first extension whereby said cooperating fastening elements are selectively engageable with certain of the fastening elements on said first extension to furnish an adjustable vamp portion, a series of fastening elements on the outer surface of said second extension disposed one to the rear of the other and a cooperating fastening element mounted on the end of the portion projecting forwardly of the toe supporting area whereby the latter may be folded upwardly and rearwardly and secured to any of the last named series of fastening elements of the second extension.
